UNITED STATES PATENT OFFICE.

SAMUEL JAMES WINN, JR., OF PLAINFIELD, NEW JERSEY.

BULLET-PROOF RIFLE-SHIELD.

1,244,679.

Specification of Letters Patent.

Patented Oct. 30, 1917.

Application filed December 12, 1914. Serial No. 876,832.

To all whom it may concern:

Be it known that I, SAMUEL JAMES WINN, Jr., a citizen of the United States, residing in Plainfield, New Jersey, have invented certain new and useful Improvements in Bullet-Proof Rifle-Shields, of which the following is a specification.

This invention aims to provide an improved shield for use in war to protect the face and shoulders of a soldier and adapted for quick and easy attachment to a rifle or machine guns or light field guns or the like. The shield is made of steel of high resistance to impact and sufficiently thick to deflect rifle bullets at two hundred yards range. It can nevertheless be made very light and compact. It may be also designed to serve as a box or pocket in which can be carried a number of rounds of cartridges.

20 The accompanying drawings illustrate embodiments of the invention.

Figure 1 is a side elevation of the shield attached to a rifle in the position of use;

25 Fig. 2 is a longitudinal section of the shield and the parts of the rifle adjacent to the lock;

Fig. 3 is a forward face elevation of the shield in the position of Fig. 1, with the rifle barrel in section.

30 Fig. 4 is a detached plan view of means for adjusting the position of the shield;

Fig. 5 is a perspective view of the shield when folded ready for transportation;

35 Fig. 6 is, in part, a side elevation and, in part, a longitudinal section showing a construction differing slightly from that in the previous figures;

Fig. 7 is a perspective view of another style of shield folded and partly broken 40 away;

Figs. 8 and 9 are, respectively, a longitudinal and transverse section of a preferred style of connection.

Referring to the embodiments of the invention illustrated, the rifle is of any usual or suitable type provided with a lock A and a barrel B on the top of which are a fixed sight C and a rear sight D adjustable for various ranges. The shields are made 50 of metal sheets or plates and comprise a lower portion E and an upper portion F connected by a hinge G forming a rule-joint which permits the parts to be folded together as in Figs. 5 and 7, but limits their 55 relative movement in the opposite direction to about the relation shown in Figs. 1, 2 and 6. The lower part of the shield is pro-

vided with a port H, Figs. 3, 5 and 7, the shape of which will depend on the design of the rifle. It must be large enough to be 60 easily passed over the muzzle and shifted to the rear. It must fit the cross-section of the rifle fairly close at a point near the lock casing where it is to be applied and it must be notched in some cases to pass over 65 projections from straps or other parts mounted upon or around the barrel. The cross-section formed by the barrel and the hand grip J increases gradually toward the rear and the port H is so shaped that it 70 will fit the cross-section of the rifle at about the point indicated and in an oblique position. In this position it will deflect the bullets and can be made of less thickness than if it were arranged to meet them 75 squarely. A strap or similar projection J' (Figs. 1 and 2) or J² (Fig. 6) is arranged on the side of the hand grip serving as a stop to limit the backward movement of the shield. The portion E of the shield is 80 also provided with a port K in line with the sights so as to permit the user to aim the rifle; this port being elongated in the vertical direction to provide for adjustments of the range, as desired.

The upper portion F carries a brace L pivotally connected to the rear face thereof and adapted to connect the shield to the rifle at a point in the rear of the lower portion of the shield. The rule-joint connection between the two portions of the shield facilitates the ready attachment of the brace L to the rifle, whatever the angle at which the portion E may stand. This brace is connected by a universal joint L' to 95 the upper portion F so that it may swing freely and thus be easily attached at its lower end and also so that it may be swung inward flat against the plate F when the shield is to be folded, as in Fig. 5 or Fig. 100 7. This brace may have its upper end connected on the middle line of the shield and be bent as in Fig. 3, so as to be out of the line of sight and so as to lie at the side of the rifle. It is provided on its lower end 105 with any usual means for quick attachment.

In the simpler constructions of Figs. 6 and 7 the brace L is provided at its lower end with a rearwardly extending button M which can be snapped into a socket N of 110 the common impulsive spring catch type fastened on the side of the rifle just in front of the lock so as not to interfere with the easy manipulation of the latter.

Means may be provided, however, for setting the lower end of the brace L at adjustable heights and thus varying the angle at which the shield shall stand, as in Fig. 1. 5 In this case the socket N is mounted on a plate O which is pivoted on the side of the gun, and the brace is provided with a button on its end similar to that in Fig. 6, but extending sidewise, so that the lower end 10 of the brace may be snapped into the socket by a comparatively slight lateral blow and will be held there against ordinary strains (being removable by a similar blow in the outward direction). The plate O is practically a gear as shown in Figs. 3 and 4, having teeth on its inner face which engage with a horizontal gear P pivoted on the underside of the rifle and carrying a handle Q by means of which the user of the rifle 15 20 may quickly elevate or lower the upper portion of the shield. (See the elevated position in dotted lines, Fig. 1).

The upper portion F of the shield (Figs. 1 and 6) is provided with a top flange R and side flanges S which serve to convert the shield into a box in which a number of rounds of cartridges can be carried either loosely or by any suitable fastenings. The upper flange R is provided with one or more 25 snap hooks T and the parts are so proportioned that the lower portion E of the shield may be closed against the flange R and held there by the fasteners T so as to form a closed box for carrying cartridges on the 30 march. Where the cartridges are fastened to the upper portion F of the shield they will be presented to the user in a most convenient place for withdrawal and insertion into the rifle when on the firing line. Eyes 35 U for attachment to a belt or shoulder strap for conveniently carrying the shield on the march are provided on the top or side flanges or both. The flanges R and S serve also to stiffen the portion of the shield to which 40 they are attached.

Any suitable detail may be used for the universal joint. In Figs. 8 and 9 I have illustrated a plate V attached to the portion F of the shield by countersunk rivets and 45 having a stem W mounted to turn freely in the stem of an eye X engaged by an eye at the upper end of the brace L. The stem W is provided with a circumferential groove through a portion of which passes a pin Y fastened in the stem of the eye X.

The shield may be further simplified, as shown in Fig. 7, by omitting the flanges on the upper portion and providing the latter merely with the straps U and snap hooks 50 T. These are sufficiently weak to be readily pressed up by the user's fingers when the shield is to be unfolded and are so shaped that in folding the shield the parts need

only to be pressed together when they will be engaged and held by the catches. 65

The shield is entirely supported, in use, upon the rifle, but is so light as not to interfere with the use thereof; and on the march the soldier's burden is so much the lighter for not including any special supporting means for the shield. The shield, therefore, combines the important advantages of lightness, ease and quickness of application, compactness on the march and a substantial degree of protection in action. 70 75

Though I have described with great particularity of detail certain specific embodiments of my invention, yet it is not to be understood therefrom that the invention is restricted to the specific embodiments described. Various modifications thereof, in detail and in the arrangement of the parts may be made by those skilled in the art without departure from the invention. 80

What I claim is—

1. A shield for rifles, comprising a plate with a port in its lower portion fitting over the barrel of the rifle so that it may be applied over the muzzle and shifted rearwardly to a point near the lock with the upper edge of said port resting on the lock casing and supporting the shield, and a brace for connecting the upper portion of the shield to the rifle at a point farther in the rear, said brace being adjustable to raise and lower the upper portion of the shield. 90 95

2. A shield for rifles comprising two portions hinged to each other and of approximately the same width so that they may be folded compactly upon one another, one of said portions being flanged so that when they are folded they form a box adapted for carrying cartridges and the like. 100

3. A detachable portable shield for rifles comprising a lower portion adapted for direct attachment on the rifle, an upper portion hinged to said lower portion and a brace connecting the upper portion to the rifle at a point in the rear of said lower portion. 105

4. A detachable portable shield for rifles comprising a lower portion adapted for direct attachment on the rifle, an upper portion hinged to said lower portion, a brace connected to said upper portion and means for adjustably connecting said brace to the rifle so as to hold the upper portion in different positions of adjustment. 110 115

In witness whereof, I have hereunto signed my name in the presence of two subscribing 120 witnesses.

SAMUEL JAMES WINN, JR.
